CLAIM

The ornamental design for a clothes hamper, as shown and described.

DESCRIPTION

FIG. 1 is a perspective view of a clothes hamper embodying our new design;

FIG. 2 is a front elevational view thereof;

FIG. 3 is a rear elevational view thereof;

FIG. 4 is a side elevational view thereof showing the side opposite to that which is shown in FIG. 1;

FIG. 5 is a top plan view thereof; and,

FIG. 6 is a bottom plan view thereof.

The surface pattern which is fragmentally shown in FIGS. 1, 2 and 5 is understood to repeat uniformly and continuously across the entire indicated surfaces.

FIG. 1

FIG. 2

FIG. 3

FIG. 4

FIG. 5

FIG. 6
